UNITED STATES PATENT OFFICE.

ALBERT W. MOYER, OF NEW YORK, N. Y.

FURNACE.

1,209,321.

Specification of Letters Patent. Patented Dec. 19, 1916.

Application filed September 25, 1915. Serial No. 52,572.

To all whom it may concern:

Be it known that I, ALBERT W. MOYER, a citizen of the United States of America, residing at New York, county and State of New York, have invented a new and useful Furnace, of which the following is a specification.

My invention relates particularly to what are known as "heat treating" furnaces.

One object of the invention is to effectively control and retain the heat and further to prevent waste and loss of heat by radiation, etc.

A special object is the provision of simple and effective means for the heat treatment of shrapnel and articles of similar character.

In the attainment of these objects I have constructed a furnace having an upper combustion chamber and a lower heating chamber, said chambers being separated by a perforated arch and the discharge from the heating chamber taking place through outlets leading from the bottom of said chamber. These outlets lead off from the heating chamber in such a way as to leave the side walls of said heating chamber solid and imperforate whereby the better to retain the heat within the heating chamber. These imperforate side walls will preferably also be provided with a layer of suitable heat insulating material.

Another feature of the invention is a hearth of improved construction made up of closely laid blocks having their upper surfaces shaped to provide channels for guiding the articles through the heating chamber.

Other features of the invention are special means for feeding the shrapnel or other objects through the heating chamber, for cooling the objects and for subjecting the objects to a second or "reheating" treatment.

Other objects and features of the invention will appear as the specification proceeds.

The accompanying drawings illustrate the invention embodied in a practical and preferred form, but I would have it understood that changes and modifications may be made without departing from the true scope and spirit of the invention.

Figure 1 is an end view of a furnace installation embodying the invention and comprising a so-called "heat treating" furnace unit and a "reheating" furnace unit, the

reheating unit being shown in section. Fig. 2 is a horizontal sectional view taken substantially on the plane of the line 2-2 of Fig. 1. Fig. 3 is a longitudinal substantially central sectional view of the heat treating furnace unit. Fig. 4 is a broken sectional view taken at the entrance end of the reheating furnace unit. Fig. 5 is a detail perspective view of the withdrawing tongs.

In the installation shown, 10 is the heat treating furnace unit, and 11 is the reheating furnace unit. These two units, except for details which will later be referred to, are substantially the same in construction so that the general description of one will suffice for both.

The interior of the furnace body is divided by an arch wall 12 into an upper combustion chamber 13 and a lower heating chamber 14, said arch wall having suitable openings or perforations 15 therein permitting heat products to pass freely from the combustion chamber down into the heating chamber. A burner 16 (or series of burners usually) discharges into the combustion chamber through a burner opening 17 (or openings) in the side of said chamber.

The waste products discharge from the heating chamber through outlet flues 20 located at the bottom portion of the chamber and extending in the present instance downwardly and inwardly from the opposite sides of the furnace into a common exit flue 21 extending longitudinally beneath the hearth of the furnace. This arrangement of the outlet flues leaves the side walls 22 constituting the sides to the heating chamber solid except for the flues 20 and therefore

for practical purposes substantially imperforate, and, therefore, better capable of retaining the heat within the heating chamber. The retention of heat within the heating chamber is further accomplished by a layer of heat insulating material such as indicated at 23. In the present disclosure the waste gases are carried from both furnaces through branch flues 24 to a common outlet stack 25. Valves 26 may be provided to regulate the flow through the outlet flues for controlling the heat in the heating chamber.

The installation illustrated is designed primarily for the treatment of shrapnel, the shrapnel being fed through the furnace in five parallel rows substantially as indicated at 30 in Fig. 1. The shrapnel are guided in

grooves formed in the hearth of the heating chamber, these grooves being provided in the present instance by means of closely laid hearth blocks 31 having the rounded 5 upper surfaces as indicated in Figs. 1 and 3 which coöperate when the blocks are laid to form longitudinal guiding grooves or channels 32.

The shrapnel are fed through the heating 10 chamber in the present instance by a pusher comprising a hydraulic or pneumatic cylinder 35 having a piston which operates a pusher-head 36. To guide and position the shrapnel for charging into the furnace, a 15 charging car 37 is here provided traveling on tracks 38 adjacent the entrance 39 to the heating chamber of the "heat treating" unit. This charging car is provided with a series of pockets or recesses 40 therein registering with the guide channels in the hearth. 20 In operation, a charge of shrapnel is placed on the car, the door 41 normally closing the entrance to the heating chamber is opened and the pusher is operated to thrust the charge into the furnace. The weight of the 25 shrapnel and the frictional engagement in the guide pockets 40 is ordinarily sufficient to cause the pusher head as it engages the shrapnel to carry along also the car thereby 30 causing the car to bridge the space left by the door, and to bring up against the outermost hearth blocks. After the car engages with the hearth in this way, the further stroke of the pusher projects the shrapnel 35 out of the pockets on the car into the guide channels on the hearth. The shrapnel are thus advanced one row at a time until the furnace is fully charged. After charging, the furnace is closed until the row of shrapnel first inserted have received the treatment predetermined upon. A fresh row of shrapnel is then charged into the furnace, this having the effect of forcing out the first 40 row of shrapnel at the discharge end of the furnace.

In addition to its function of charging the shrapnel into the furnace, the pusher is constructed and arranged to withdraw the charging car out of the way of the 45 descending door or closure 41, there being provided for the purpose a lug 45 on the car arranged to be engaged by the pusher head 36 upon the return stroke of said pusher head. It will be clear from this that the engagement of these parts will cause the pusher upon its retractive movement to pick up the charging car and draw it back to its normal loading position.

Suitable provision is made for discharging 50 or withdrawing the treated objects from the heat treating furnace, and transferring them to the reheating furnace. Such means here takes the form of withdrawing tongs 50, supported at the discharge end of the 55 heat treating unit and arranged to carry

said objects from this first furnace to the second or reheating furnace. In the illustration the furnaces are disposed side by side with the exit end 51 of the first furnace adjoining the entrance end 52 of the other 70 furnace, and a quenching tank 53 extends across these faces of the furnaces, in which the objects are cooled while being transferred from one furnace to the other.

The withdrawing device here disclosed is 75 made up of a body 55 adapted to be rested upon a shelf 56 at the discharge end of the heat treating furnace, and provided with pockets 57 therein registering with the guide channels of the hearth. When the withdrawing device is thus supported at the discharge end of the heating chamber as indicated in Fig. 3, and the charging pusher is 80 operated, the foremost row of shrapnel will be forced off into the pockets 57 in the withdrawing device.

The shrapnel or other objects may be held in the withdrawing device by means of a flange 58 adapted to overlie the ends of the objects and gripping fingers 59 adapted to 90 engage the opposite ends of the objects. In the illustration these fingers project into the open outer ends of the shrapnel shells 30, and the opposite ends of the shrapnel shells are left with lugs 60 engaging beneath the 95 holding flange 58. The gripping fingers are shown as being opened up to receive the objects by means of grips 61 pivoted on the handles 62 of the tong and connected by rods 63 with rock arms 64 on the rock shaft 10 65 which mounts the gripper fingers.

The withdrawing device is shown movably supported by a hydraulic or like hoist 70 arranged to travel on a track 71 extending above the quenching tank and across the 10 adjoining ends of the two furnaces. The hoist is provided with a hook 72 engaging with an eye 73 on the tongs.

After the tongs have received a load of shrapnel or other objects as indicated in 110 Fig. 3, the tongs are withdrawn clear of the supporting shelf 56 by means of the handles 62 and are allowed to swing down into an upright position. The hoist is then operated to dip the tongs carrying the objects 115 down into the tank. In this way the objects can be plunged straight down into the tank so as to temper them evenly all around. The hoist can then, without lifting the tongs, be traveled along its track to a point in 120 front of the reheating furnace. This passage through the tank properly cools the objects and also circulates the cooling fluid so as to keep it at an approximately uniform 125 temperature. Before inserting the objects in the reheating furnace the tongs are rotated half way around, from the dotted line position in Fig. 3 into the position indicated in dotted lines in Fig. 4. This is usually done before lifting the tongs from the tank. After 130

the hoist is operated to lift the tongs from the tank, the tongs are swung on the pivot connection provided by the hook and eye joint 72-73 and pushed over to carry the objects into position resting on the charging shelf 75 at the mouth of the reheating furnace. This shelf is, as indicated in Fig. 4, inclined downwardly away from the mouth of the furnace so as to cause the objects to 10 drain any liquid they may contain back into the tank.

Suitable means are provided for charging and feeding the objects through the reheating furnace. The means here disclosed for 15 this purpose is a pusher made up of two cylinders 80 located at opposite sides of the furnace and having their piston rods 81 connected by a bar 82 forming a pusher head for engaging the objects rested on the charging shelf 75. When the objects have been 20 placed by the tongs on said charging shelf, as shown in Fig. 4, with the pusher head 82 engaging in rear of the objects, the tongs is manipulated to release it and remove it from 25 the objects and the pusher is operated to charge the objects into the furnace. After thus discharging its load, the tongs may be carried back to a position in front of the first furnace. In the illustration, Fig. 2, the 30 track 71 is shown made in the form of a loop. This permits the use of several hoists and facilitates the return of the hoists and tongs back to the first position.

The charging pusher for the reheating 35 furnace serves to feed the objects through this furnace in the same way as was described in connection with the pusher of the first furnace. In this reheating furnace the temper is drawn and the shrapnel or other 40 objects are annealed to the extent determined upon. The treated objects may be discharged from the discharge end 85 of the annealing furnace onto a car or suitable conveyance, if so desired.

From the foregoing it will be apparent 45 that with my invention shrapnel or objects of the like character can be readily and effectively treated without any loss of time in handling and at a considerable saving of time over present methods of treating each shrapnel separately. Furthermore, the furnace constructed according to my invention, by reason of the conservation and utilization of all the heat is economical in operation 50 and can be so controlled as to secure the most effective results. The hearth blocks are preferably made of iron or other heat retaining material, and so serve in addition to guiding the objects through the chamber, 55 to retain the heat and keep the working chamber at a practically uniform temperature. The hard rounded surfaces of these blocks provide efficient guiding channels in which there is no danger of the objects becoming caught or clogged and the blocks 60

though very durable and lasting may, if they should wear out, be very readily replaced.

The location of the exit flues in both side 70 walls of the furnace body and near the bottom portion of the heating chamber causes the heated gases to pass evenly down through the heating chamber and this construction, wherein the side walls of the furnace body which form the sides of the heating chamber are free of perforations above 75 the exit flues, eliminates the "striped effect" present in prior furnaces wherein the side walls of the heating chamber are perforated by flues and hence are incapable of retaining the temperature uniformly. These solid side walls retain the heat to a uniform extent throughout and so radiate heat into the heating chamber uniformly throughout their extent;

Another important feature of the structure illustrated is that the flow of hot gases through the furnace is accomplished through the action of burners, said burners forcing the gases downward through the 90 perforated arch, through the heating chamber and out the downwardly and laterally extending portions of the exit flues to the upright stack 25 which is simply a vent located at a convenient point for conducting 95 off the waste gases.

It will be understood that the terms employed in disclosing and claiming this invention are used in a descriptive rather than in a limiting sense, except in so far as may be required by the prior art.

What I claim is:

1. A gas or oil fired furnace comprising a furnace body having side walls and a perforated arch extending across between 105 said side walls of the furnace body and dividing the interior of the same into a lower heating chamber and an upper combustion chamber disposed directly and wholly above the heating chamber, the combustion chamber thus provided having burner openings therein and the heating chamber having exit flues in both side walls thereof leading from the bottom portion of the chamber, the side walls of the furnace 110 body forming the sides of the heating chamber being otherwise free of perforations therein whereby to retain the temperature uniformly throughout said side walls and thereby radiate heat uniformly from said 115 walls into the heating chamber and burners discharging through the burner openings into the combustion chamber.

2. A gas or oil fired furnace comprising a furnace body having side walls and a perforated arch extending across between the side walls of the furnace body and dividing the interior of the same into a lower heating chamber and an upper combustion chamber disposed directly and wholly above the heat- 120 125 130

ing chamber, the combustion chamber thus provided having burner openings therein and the heating chamber having exit flues in both side walls thereof leading from the 5 bottom portion of the chamber, the side walls of the furnace body forming the sides of the heating chamber being otherwise free of perforations therein whereby to retain the temperature uniformly within the heating chamber, a layer of heat insulating material on the furnace body and burners discharging through the burner openings into the combustion chamber.

3. A gas or oil fired furnace comprising 15 a furnace body having side walls and a perforated arch extending across between the side walls of the furnace body and dividing the interior of the same into a lower heating chamber and an upper combustion chamber 20 disposed directly and wholly above the heating chamber, the combustion chamber thus provided having burner openings therein and the heating chamber having exit flues in both side walls thereof leading from the 25 bottom portion of the chamber, the side walls of the furnace body forming the sides of the heating chamber being otherwise free of perforations therein whereby to retain the temperature uniformly within the heating 30 chamber, dampers controlling the flow through the exit flues and disposed adjacent the junctions of said flues with the heating chamber to thereby control the flow substantially at the source and burners dis-

charging through the burner openings into 35 the combustion chamber.

4. A gas or oil fired furnace comprising a furnace body having side walls and a perforated arch extending across between said side walls of the furnace body and dividing 40 the interior of the same into a lower heating chamber and an upper combustion chamber disposed directly and wholly above the heating chamber, the combustion chamber thus provided having burner openings therein 45 and the heating chamber having exit flues located in the side walls substantially at the bottom of the heating chamber and said side walls which form the sides of the heating chamber being free of perforations above 50 said exit flues therein to thereby retain heat uniformly throughout the extent of the side walls and to radiate heat uniformly into the heating chamber, the exit flues aforesaid extending downwardly and thence laterally 55 from beneath the furnace body, an upright exhaust vent separated from the furnace body and in communication with the laterally extending portion of the exit flues and pressure burners discharging in through the 60 burner openings into the combustion chamber and forcing gases of combustion down through the perforated arch into the heating chamber and from said heating chamber down and out the exit flues up the upright 65 vent.

ALBERT W. MOYER.
